[57] CLAIM

The ornamental design for a stand for a stringed musical instrument, as shown and described.

DESCRIPTION

FIG. 1 is a perspective view of one embodiment of a stand showing my new design;

FIG. 2 is a top plan view of the embodiment shown in FIG. 1;

FIG. 3 is a bottom plan view of the embodiment shown in FIG. 1;

FIG. 4 is a front elevational view of the embodiment shown in FIG. 1;

FIG. 5 is a back elevational view of the embodiment shown in FIG. 1;

FIG. 6 is a side elevational view of the embodiment shown in FIG. 1, the right side elevational view being identical to the left side elevational view;

FIG. 7 is a perspective view of another embodiment of a stand showing my new design;

FIG. 8 is a top plan view of the embodiment shown in FIG. 7;

FIG. 9 is a bottom plan view of the embodiment shown in FIG. 7;

FIG. 10 is a front elevational view of the embodiment shown in FIG. 7;

FIG. 11 is a back elevational view of the embodiment shown in FIG. 7; and,

FIG. 12 is a side elevational view of the embodiment shown in FIG. 7, the right side elevational view being identical to the left side elevational view.
